HANS VON KRAMER, OF EDGBASTON, BIRMINGHAM, ENGLAND.

MEANS FOR THE REGULATION OR CONTROL OF RAILWAY AND LIKE TRAFFIC.

1,094,407.

Specification of Letters Patent. Patented Apr. 21, 1914.

Application filed February 5, 1913. Serial No. 746,347.

To all whom it may concern:

Be it known that I, HANS VON KRAMER, subject of the King of Great Britain, residing at Kramersruhe, Wheatsheaf Road, 5 Edgbaston, Birmingham, in the county of Warwick, England, have invented a new and useful Means for the Regulation or Control of Railway and like Traffic; and I do hereby declare the following to be a full, 10 clear, and exact description of the same.

My invention comprises improvements in means for the regulation or control of railway and like traffic and refers to that class of apparatus or system wherein a line wire 15 is laid parallel to the track in combination with an inductive frame carried by the vehicle, the signaling communication or connection being inductively transmitted between the line wire and the frame.

Heretofore various arrangements have 20 been proposed for warning the engine driver that he is approaching the signal, and inductive means have been proposed for this purpose comprising a line circuit laid in 25 proximity to the signal so arranged that when the train passes through the inductive field a warning is conveyed to the engine driver to indicate the proximity of a signal, but in all such cases the warning was dependent upon the presence of current in the 30 line wire so that if the current failed in the line wire the warning would not be given; and it is the object of my invention to provide a means whereby the warning is given 35 by the absence of the induced current so that in the event of failure of the current the engine driver would be at once advised, and the trains might be entirely stopped.

Referring to the drawings:—Figure 1 is a 40 diagrammatic plan of one form of the line installation. Fig. 2 is an electrical diagram illustrating the parts carried by the vehicle. Fig. 3 is a diagram in plan but showing the signal in elevation of a modified form of the 45 invention.

In carrying my invention into practice as 50 illustrated upon the accompanying drawings at Figs. 1 and 2 the train (not illustrated) carries a wire frame 2 consisting of a considerable number of turns of wire coiled around the engine and arranged to travel in proximity to a wire 3 disposed parallel to the track, this wire 3 being above the ground though it may be arranged in 55 any other suitable manner. Such a line wire would extend throughout the track or

for a length as illustrated in Fig. 1 corresponding with a signaling section as illustrated in Fig. 3, current being sent through the line wire by means of an electrical generator indicated by 5 and located at a suitable line station. 60

The signals are indicated by 6 and immediately in front of each signal or point at which it is desired to warn the driver the line wire is divided into two electrically parallel parts formed by the addition of the wire marked 7. It will be obvious that half the current will pass through the wire 7 and half through the part marked 3^a and both 70 of these wires 3^a and 7 will induce current in the frame 2 of the vehicle, but as the wire 3^a is on the opposite side of the train to the wire 7 it will induce the current into the opposite longitudinal limb or side of 75 the frame to that in which the wire 7 is inducing current. Therefore current will be induced on both sides of the frame, the induced current seeking to travel in the same longitudinal direction, but as the frame on 80 the vehicle is endless the two induced currents will oppose, and neutralize each other so that there is no resultant current induced in the frame. Thus it will be seen that when the train is passing over the greater 85 part of the wire 3 current will be induced in the frame which is arranged to render the warning device on the train inoperative, but when the train is passing over the parts 3^a and 7 immediately in front of the signals the induced current will cease and the 90 warning device will operate in manner hereinafter explained. 95

The frame 2 controls a relay device and as illustrated the frame is in circuit with the coil wire 8 of a relay which is according to the prior Patent No. 1067823, dated July 22d, 1913, of Hans von Kramer and Gisbert Kapp. When current passes through the wires 8 it causes the reed 9 to 100 vibrate which breaks a second circuit between the contact springs 10. In Fig. 2 the end of the reed only is shown, and the construction of the relay and disposition of the reed will be understood from reference to 105 the prior specification above referred to. These contact springs 10 form part of a second circuit which include a battery 11 and solenoid switch 12 being so arranged that the solenoid switch is raised to break a 110 third circuit at 13, 13, when the contacts 10, 10 engage to complete the second circuit,

but when the contacts 10 disengage the solenoid switch connects the contacts 13, 13, and establishes a third circuit. The third circuit again includes the battery 11 and in addition a second solenoid 14 which normally raises a lever 15 which controls a warning device indicated by 16 in such manner that when the lever is raised the warning device is inoperative. When the solenoid 14 is deenergized the lever falls and actuates the warning device which may be either audible, optical or mechanical and may be arranged to either simply warn the driver that he is approaching the signal or 10 danger point, or it might be arranged under certain circumstances to entirely stop the train. It will be seen from this explanation that when there is no induced current in the frame 2 the reed 9 will immediately 15 come to rest, allowing the contacts 10 to engage when the second circuit is completed and the solenoid switch 12 operated to disengage the contacts 13, 13 which deenergizes the solenoid 14 to operate the warning device. 20

In the modified form of the invention shown by Fig. 3 in front of each of the signals 3 are three supplemental wires 7 arranged to give a momentary warning to the 25 driver as by ringing a bell three times indicating to him that he is approaching the signal. Adjacent to the signal the line wire is so arranged that if the signal is up *i. e.* in the "blocked" position as employed in 30 Great Britain the line wire will be non-inductive at this place, the non-inductive part being of a sufficient length to stop a train when approaching the signal, while 35 when the signal is in the "clear" position the wire at this point is inductive in exactly the same way as the main length of wire. The signal 17 is adapted to engage with and 40 electrically connect fixed contacts 18, 19, when the signal is in the horizontal or "blocked" position and to engage with and 45 electrically connect contacts 20, 21 when the signal is in the "clear" position. The main wire 3 is connected to a terminal 22 which is also connected to a wire 3^b and also being 50 connected to a supplemental wire 7^a, the wires 3^b and 7^a being connected together at 55 23 and thence by a wire 24 to the contact 19 which is connected to a contact 18 by a bridge plate 17^a on the signal, the contact 18 being connected to the contact 21 which is 60 connected to the wire 3 through the medium of the wire 25 and terminal 26. Thus when the signal is in the "blocked" position the wire will be non-inductive in similar manner to the parts 3^a and 7 previously described, this part being however of a sufficient length to entirely stop the train if attempting to run over this portion of the line when the signal is in the "blocked" 65 position. When the signal is in the "clear" 70

position the connection between contacts 18 and 19 is broken and the wires 3^b and 7^a being connected to the open terminal 19 by wire 24 no current will pass through, while the contacts 20 and 21 are completed. The 75 terminal 22 is connected to the contact 20 by the wires 27 and 27^a, the latter being at a distance from the track, while the contact 21 is as previously stated connected to the terminal 26 by the wire 25. Thus when the 80 signal is in the "clear" position the part of the wire 27 will be capable of inducing current in the frame in exactly the same way as is the main wire 3. The arrangement of the signals as illustrated according to the 85 British practice, *i. e.* the signal arm being dropped to indicate that the line is clear, it will be obvious that it might be applied to signals which work in the reverse manner in which case the circuits will be oppositely 90 arranged so that the line is non-inductive when the signal is lowered.

In the various views the rails are indicated by dotted lines, while as shown in Fig. 3 the out and return portions of the 95 line wire may be mutually crossed at intervals to render the circuit non-inductive to outside disturbing influences.

The parts of the line wire may be made more inductive by any suitable means such as that illustrated and previously described. 95

The invention might also be applied to warning the driver when approaching a "curve" or dangerous part of the track such as level crossing, gates or barriers, in 100 which case the position of the gates might control the circuits in similar manner to the signal as previously described, the gates or barriers constituting the "indicator" instead of the signal arm and carrying contacts arranged in the same way. 105

It will be obvious from the explanations given that in the event of failure of the current the whole of the system would become non-inductive so that the effect of an electrical break down would only be to stop the trains, there being no risk of accidents as in the forms of inductive signaling wherein the transmission of the signal depends upon the presence of the induction. 110

What I claim then is:—

1. In apparatus for the regulation or control of railway and like traffic, the combination of a line wire laid parallel to the track of the vehicle; means for continuously passing periodic electric current through said line wire; a wire frame carried by the vehicle in inductive relation with the line wire; a signal receiving device carried by the vehicle inoperative while current is induced into the frame from the line wire but operative when the induced current ceases; and means for rendering certain parts of the line wire non-inductive to the frame, without interrupting the current 120 125 130

passing in the line wire so that the non-inductive parts will operate to convey signals while when the vehicle is passing over the non-inductive lengths the signal receiving device will be inoperative.

2. In apparatus for the regulation or control of railway and like traffic, the combination of a line wire laid parallel to the track of the vehicle; means for continuously passing periodic electric current through said line wire; a wire frame carried by the vehicle in inductive relation with the line wire; a signal receiving device carried by the vehicle inoperative while current is induced into the frame from the line wire but operative when the induced current ceases; a supplemental wire laid parallel to the line wire at certain portions, said supplemental wire being in inductive relation with the opposite limb of the frame to that which the main line wire is in inductive relation with, and whereby the currents induced in the frame by the two parallel parts of the line wire are caused to neutralize each other.
3. In apparatus for the regulation or control of railway and like traffic, the combination of a line wire laid parallel to the track of the vehicle; means for continuously passing periodic electric current through said line wire; a wire frame carried by the vehicle in inductive relation with the line wire; a signal receiving device carried by the vehicle inoperative while current is induced into the frame from the line wire but operative when the induced current ceases; an indicator controlled by the signal receiving device; and means controlled by the position of said indicator whereby when the indicator is in the "blocked" position a portion of the line wire is rendered non-inductive to the frame without interrupting the passage of the current in the main length of the line wire while when the indicator is in the "clear" position the said portions are made inductive to the frame.
